UNITED STATES PATENT OFFICE.

LAWRENCE M. ENDRES AND MICHAEL A. ENDRES, OF DANE, WISCONSIN.

SPLASH LUBRICATING SYSTEM.

Application filed November 17, 1921. Serial No. 515,778.

To all whom it may concern:

Be it known that we, LAWRENCE M. ENDRES and MICHAEL A. ENDRES, both citizens of the United States, and residents of Dane, 5 in the county of Dane and State of Wisconsin, have invented certain new and useful Improvements in Splash Lubricating Systems; and we do hereby declare that the following is a full, clear, and exact description 10 thereof.

Our invention refers to splash lubricating systems employed in connection with a splash pan or the crank case of internal combustion engines.

15 The invention has for its primary object the provision of a simple, economical and effective oil reservoir for said crank cases or splash pan, having means for automatically controlling the level of oil within the 20 crank case with respect to the reservoir.

It contemplates especially a gravity feed from an air tight reservoir having a cut-off arranged adjacent the crank case operating to control the amount of oil fed into the 25 crank case by reason of a device wherein the level of the oil in the crank case controls the admission of air into the reservoir. The exclusion of air from the reservoir prevents a feeding of oil because of the 30 formation of a vacuum in the reservoir.

An additional feature of our invention is the provision of a device whereby the air fed into the reservoir and associated pipes is kept clean as it is gotten from the crank 35 case.

With the above objects in view, the invention consists in certain peculiarities of construction and combinations of parts as are hereinafter set forth with reference to the 40 accompanying drawings and subsequently claimed.

Figure 1 shows a plan view of the reservoir, and part of the crank case in section.

Figure 2 is a cross section substantially on 45 the line 2—2 of Figure 1.

Figure 3 is a cross section on the line 3—3 of Figure 1; and

Figure 4 is a detail of a bushing.

Reservoir 10 is affixed at 11 to the horizontal flange marking the union of the crank case castings. Oil outlet pipe 12 leads from the bottom thereof, and is provided with a control valve 13 which may be operated to cut off the flow of oil entirely. Air inlet 50 pipe 14 communicates with the top of reser-

voir 10. This pipe may be made of rather light material to facilitate its sliding into member 15 which is provided with bushing 16, having a follower 17 and packing 18 to prevent the escape of fluid. 60

Member 15 is provided with a nipple 19 threaded in the crank case. Pipe 12 is suitably connected to member 15 at 20. Goose neck 21 leads from member 15 and has a relatively short arm connected to pet cock 65 22 provided with a nipple 23, threaded into the crank case. Pet cock 22 is located above and to one side of member 15. Member 15 is chambered at 16 so as to provide communication with pipe 12, air inlet pipe 14 and 70 goose neck 21. The air inlet pipe 14 may be pushed downwardly into chamber 16 or withdrawn to any desired degree.

In Figures 3 and 4, the slant or character of air inlet pipe 14 appears. This slant, 75 however, is not necessary to our invention and, if desired, the pipe may be positioned vertically. Stop cocks 24 and 25 may be provided.

In the operation of the device, control 80 valve 13 is operative to permit the exit of oil from the reservoir 10 into pipe 12. If there is no oil in the crank case, the fluid is fed into pipe 12, member 15 and nipple 19, 85 into the crank case. At the same time there is a flow of air upwardly in air inlet pipe 14 to the top of reservoir 10, thus breaking the vacuum in reservoir 10 and permitting the free outflow of the oil which rises in the crank case. Even after the oil in the crank case 90 has passed above nipple 19, the flow of oil will continue, as air is received through nipple 23, pet cock 22 and goose neck 21, into chamber 15 whence it flows into air pipe 14. This operation continues until the level of the liquid is above the end of air inlet pipe 14. At this point the flow of oil stops as 95 air is not being communicated to the reservoir 10. Hence it appears that the level of the fluid in the crank case is determined by the location of the terminus of air inlet pipe 14. Goose neck 12 need not necessarily connect with the crank case, but such location is useful in that it keeps the air which is fed 100 into air inlet pipe 14 clean. Goose neck 12 may receive the air from any source. Pet cocks 24 and 25 may be used to perform their customary function in connection with crank cases, if so desired, but in view of the automatic feed, they may be dispensed with. 110

We claim:

1. An oil feed mechanism for crank cases comprising a reservoir and oil pipe extending therefrom, an air inlet pipe extending therefrom, a chambered member receiving said pipes a connection between said member and the crank case, said connection having a duct therein, the end of said air inlet pipe extending through an opening in said chambered member and slideable upwardly in said opening to regulate the height of oil in said crank case, and a second air inlet pipe communicating with said chambered member.
2. An oil feed mechanism for crank cases comprising a member, a connection leading from said member and having a duct therethrough, a crank casing receiving said connection, an air inlet pipe and an oil pipe communicating with said member, a second air inlet pipe communicating with said member and vertically slideable therein, said second air inlet pipe terminating at a point below the end of said first mentioned air inlet pipe and a reservoir receiving said second air inlet pipe and said oil pipe.
3. An oil feed mechanism for crank cases comprising a chambered member, a nipple

thereon, a crank case receiving said nipple, air inlet means communicating at one end with said crank case and at the other end with said chambered member, an oil pipe and an air pipe communicating with said chambered member and a reservoir receiving said oil pipe and said air pipe, said air pipe being adjustable in said chambered member to regulate the height of the fluid received in said crank case.

4. An oil feed mechanism for crank cases comprising a crank case, a chambered member communicating therewith, a pet cock on said chambered member, a second pet cock communicating with said crank case, a pipe connecting said second pet cock and said chambered member, an oil pipe connected to said chambered member, a third pipe communicating with said chambered member and a reservoir receiving said oil pipe and said third pipe.

In testimony that we claim the foregoing we have hereunto set our hands at Dane, in the county of Dane and State of Wisconsin.

LAWRENCE M. ENDRES.
MICHAEL A. ENDRES.
